UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

1,412,374.

Specification of Letters Patent. Patented Apr. 11, 1922.

Original application filed June 19, 1919, Serial No. 305,237. Divided and this application filed February 18, 1921. Serial No. 446,054.

To all whom it may concern:

Be it known that I, JESSE A. B. SMITH, a citizen of the United States, residing at Stamford, in the county of Fairfield and 5 State of Connecticut, have invented certain new and useful Improvements in Typewriting Machines, of which the following is a specification.

This invention relates to typewriting machines, and particularly to means to facilitate the insertion of a work-sheet from the rear of the platen; and is a division of my application No. 305,237, filed June 19, 1919, (now Patent No. 1,377,446, granted May 15 10/21.)

Heretofore, difficulty has been experienced in inserting a work-sheet from the rear over a pack of sheets held in the machine, especially when the bottom ends of the pack of 20 sheets are near the bottom of the paper-table and a short distance from the rear feed-rolls.

To overcome the above-mentioned difficulty, the outer sheet of the pack, which may 25 be a carbon-sheet, may be made longer to form a tab, which projects beyond the bottom edges of the rest of the sheets, so that the tab may lie against the rear paper-table when the bottom edges of the other sheets are 30 near the rear feed-rolls. When the additional work-sheet is to be inserted around the pack in the machine, the typist lifts the tab away from the paper-table and inserts the sheet behind said tab; the tab thus serving 35 to guide the work-sheet past the edges of the other sheets, after which it may be moved around the platen between the paper-table and the pack of work-sheets to the printing point.

40 Other features and advantages will hereinafter appear.

In the accompanying drawings,

Figure 1 is a sectional side view of a typewriter carriage, illustrating the utility of the 45 invention.

Figure 2 is a perspective view, showing the relationship of the various sheets.

The invention is herein illustrated in connection with an Underwood typewriter carriage, which comprises a platen 1 journaled 50 by its axle 2 in end plates 3 of the platen-frame, which forms part of the carriage 5, and in which it is adapted to be rotated in the usual manner.

A proof or record-sheet 8 may be joined 55 at the leading end by means of clips 9 to a carbon-sheet 10 of the width of a memorandum sheet 11. The carbon-sheet 10 and proof-sheet 8 are passed together over the usual paper-table 12, between the usual adjustable edge-gages 13, to the rear feed-rolls 14, from which they pass forwardly and upwardly, past the front feed-rolls 15 to the printing line. Before reaching the printing line, the leading edges 17 may engage paper-fingers 18, which extend down almost to the feed-rolls 15, and tend to guide the record or proof-sheet to the rear of a paper-chute 19 held in front and above the platen.

The chute 19 may exert a slight pressure 70 by its lower edge against the pack of sheets comprising the record-sheet 8 and the carbon 10 to assist in holding said pack against sliding on the platen 1, thus permitting the feed-rolls 14 and 15 to be cast off by the 75 usual actuating handle (not shown). The memorandum sheet may then be inserted around the platen on the outside of the pack. Usually, one entry is made on the memorandum sheet 11, after which it may be removed 80 and another memorandum sheet inserted around the platen. In this way the entries made on the various memorandum sheets are copied on the record-sheet.

To prevent interference of the leading 85 edge of the memorandum sheet when inserting the latter, which may be obstructed by the bottom edges of the pack of sheets in the machine when said edges are between the platen and the paper-table, the bottom edge 90 of the outer sheet of the pack is extended so as to form a tab 20, which may lie in a convenient place to be lifted away from the table 12 by the typist, so that the memorandum sheet may be inserted behind it and 95 slidden down over the paper-table 12 and the feed-rolls 14 and 15 to the printing point and the chute 19, which locates the memorandum sheet crosswise of the record-sheet.

After the memorandum sheet has been adjusted relatively to the record-sheet, the feed-rolls may be thrown against the platen to hold the sheets while typeing. It will be understood that the platen may be line-spaced if more than one entry is to be made. 105

Variations may be resorted to within the scope of the invention, and portions of the improvements may be used without others.

Having thus described my invention, I claim:

1. In combination, a record-sheet to receive carbon impressions in a typewriting machine, a carbon-sheet, means to fasten said sheets together at their leading portions, and a tab, extending to the rear from said carbon-sheet beyond the end of said record-sheet, of sufficient dimensions to be convenient to grasp, to assist in introducing a work-sheet around said record-sheet.

2. In combination, a record-sheet, a carbon-sheet, means to fasten said carbon-sheet

in position upon said record-sheet to enable introduction of the former into a typewriting machine when the latter is introduced, and a tab extending to the rear from said carbon-sheet beyond the end of said record-sheet sufficiently to be grasped conveniently to assist in guiding, outside of the record-sheet, a work-sheet on which type impressions are to be made.

JESSE A. B. SMITH.
